UNITED STATES PATENT OFFICE

EDWARD R. TURNER, OF HOLLY, COLORADO

DOOR OR GATE OPERATING DEVICE

Application filed October 30, 1928. Serial No. 316,053.

This invention relates to doors and gates and has special reference to vehicle operated doors and gates.

One important object of the invention is to provide an improved form of door and gate hanging and operating device especially adapted for use in connection with garages, farm and road gates and other like closures for buildings, fields and roadways.

10 A second important object of the invention is to provide an improved form of supporting rail for use in connection with devices of this description, the rail being arranged to support the closure, whatever its 15 type, centrally of the opening to be closed.

A third important object of the invention is to provide improved operating means for such closures.

With the above and other objects in view 20 as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a front elevation, partly in section, of a closure and operating means constructed in accordance with this invention, the closure in the present instance being in the form of a garage door.

Figure 2 is a section on the line 2—2 of Figure 1.

Figure 3 is an enlarged detail showing the treadle in side elevation, the view being partly in section.

40 Figure 4 is a plan view of the treadle and adjacent parts.

Figure 5 is a view similar to Figure 1 but showing a modified form of the invention.

Figure 6 is a section on the line 6—6 of Figure 5.

Figure 7 is a detail section on the line 7—7 of Figure 1.

Figure 8 is a detail section on the line 8—8 of Figure 1.

50 Figure 9 is a face view of a door constructed

in accordance with this invention showing the same in several positions.

Figure 10 shows a convenient mode of rigidly attaching the curved rail 16 to the rod 15.

While the invention has been here shown 55 as applied to a garage door it is to be understood that this arrangement is not restricted to any particular type of door or gate but the principles involved may be utilized in

connection with doors, gates, barriers and 60 the like wherever located. Therefore the

words "frame" and "closure" as used herein 65 are to be understood in their broadest sense the word "frame" being understood as mean-

ing any kind of supporting structure such as 65 a door frame, gate posts and the like, and the

word "closure" including doors, gates for 70 all purposes and other types of barriers, the only restriction being that such closures are

of the laterally movable type. Furthermore, 70 it is to be understood that the present disclosure shows but two of many forms and

uses of the invention.

In the forms here shown there is disclosed 75 a door frame 10 situated in the wall 11 of a building such as a garage or the like.

In the form shown in Figure 1 this door 80 frame provides an opening which is normally closed by a door 12 having secured to its

front or outer face a pair of track wheels 80 13. To one side of the frame 10 and spaced

forwardly therefrom is fixed a post 14 which, 85 for the purposes of this invention, is consid-

ered as part of the frame. Extending through the upper part of the post 14 is a 85

rock shaft 15 carrying rigidly attached thereto between the post 14 and frame 10 an arcuate track 16 consisting of a bar of metal curved

to have its convex edge on its underside. On 90 this rail rests the wheels 13 and it will be

obvious that whatever the position to which the rail 16 may be swung the wheels will lie

opposite each other in the same horizontal line since they are spaced equally on oppo-

site sides of the center of gravity of the door 95 and the curvature of the rail 16 is uniform

throughout. It is also to be noted that the rail is attached to the shaft 15 across the

frame and terminates in an end 17 adapted

to rest on a stop 18 and having an eye 19 to 100

which is connected one end of a spring 20. This spring has its other end connected to a post 21 and thus serves to hold the rail yieldably in position to cause the door to hang centrally of the door opening. The other end of the rail extends outwardly and curves upwardly from the shaft 15 and is bent at its end to provide a stop 22 to prevent the wheels from accidentally rolling off the rail. A suitable mode of rigidity attaching the curved rail 16 to the rod 15 is shown in Fig. 10. Here the top of the rod 15 is shown as flattened or concaved, and a strong screw is shown at S for rigidly connecting the two elements. When the rod 15 is rotated a little, by a downward movement of the rock arm 23 in Fig. 1, the rail 16 is rocked thereby on the rod 15 as a pivot. The rod 15 is on the bottom side of rail 16 so as not to interfere with rollers 13.

In order to tilt the rail there is fixed to the shaft 15 a rock arm 23 which is connected by a link 24 to a rock arm 24' fixed on a rock shaft 25 extending transversely in front of the door opening, a suitable covered trench or pit 26 being provided for this rock shaft and the bearings 27 which support it. In each form here shown there is provided a treadle which extends through a suitable notch cut in the bottom of the door and this treadle is formed by a pair of members 28 aligned in plan and normally inclined downwardly from their adjacent ends and having their remote ends connected to the flooring 29 by hinges 30. Slotted plates 31 are secured to the sides of one of these members 28 and their slotted ends embrace the other member 28 and are secured thereto by pins 32. From one of these plates extends a projection 33 and, in the form shown in Figure 1, this projection is connected by a link 34 with a rock arm 35 fixed on the shaft 25.

In the form of the invention shown in Figure 5 the post 14 is omitted and the rail 16 is fixed on a rock shaft 36 supported in the frame 10. In this form wheels 37 run on the track 16, being connected to the door 12 by hangers 38 and being positioned on opposite sides of the shaft 36. A rock arm 39 extends from the shaft 36 and is connected by a cord or wire 40, which is led to proper position by idler pulleys 41, with the treadle projection 33. One or more guides 42 may be used to guide the rail to move in a vertical plane and guide means 43 is used at the bottom of the door to prevent swinging by the wind or, in the case of gates, by animals. Also latch means 44 of suitable type may be used to latch the door against movement until the treadle is started down.

In operation a vehicle approaching the door will be guided so that the wheels on one side will run over the treadle and depress it. This will effect rocking of the rail by its supporting shaft and the door will roll to

open position. After the vehicle rolls off the treadle the rail will move to normal position under the influence of the spring and the door will close.

It is to be noted that the treadle will be made of sufficient length to permit the vehicle to roll entirely past the gate or door before it starts to close. Also, while there has been here shown a door opening to the right, the device may be made to open to the left by a mere reversal of the parts and that double doors, one sliding to the right and the other to the left, may be used by mere duplication of parts.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

As shown in the drawing, the members 28 may be made of narrow slats, to prevent stock from standing on them, which would of course open the gate. When used on a garage door or barn door, a simple board could be used.

Having thus described the invention, what is claimed as new, is:

1. In a door and gate opening and closing device, a frame, a closure, a horizontal shaft journalled in said frame, an arcuate track fixed intermediate its ends to said shaft with its lower edge convex, roller hangers running on said track and carrying said closure, a rock arm fixed to the shaft, to rock the same and tilt the track, a link extending downwardly from the rock arm, a rock shaft below the level of the closure, a rock arm fixed on the rock shaft and having the lower end of the link connected thereto, and vehicle operated means for actuating said rock shaft.

2. In a door and gate opening and closing device, a frame, a closure, a horizontal shaft journalled in said frame, an arcuate track fixed intermediate its ends to said shaft with its lower edge convex, roller hangers running on said track and carrying said closure, a rock arm fixed to the shaft, to rock the same and tilt the track, a link extending downwardly from the rock arm, a rock shaft below the level of the closure, a rock arm fixed on the rock shaft and having the lower end of the link connected thereto, a second rock arm fixed on said rock shaft, and a treadle in the path of vehicle wheels and having said last rock arm connected thereto.

In testimony whereof I affix my signature:
EDWARD R. TURNER.
